Patented Apr. 14, 1970

217,200

HAIR-DO PROTECTOR

Mario Lupo, 3318 W. Peterson Ave.,
Chicago, Ill.

Filed Dec. 26, 1967, Ser. No. 9,918

Term of patent 14 years

Int. Cl. D28—02

U.S. Cl. D86—10

FIG. 1 is a rear perspective view of a hair-do protector showing my design in the use position;

FIG. 2 is a front perspective view thereof; and

FIG. 3 is a plan view thereof in fully opened position.

I claim:

The ornamental design for a hair-do protector, substantially as shown.
